SEY, A CORPORATION OF NEW JERSEY.

SHOE AND METHOD OF MAKING SAME.

Application filed August 15, 1924. Serial No. 732,230.

This invention relates to shoes and to methods for use in their manufacture. More particularly it has to do with the preparation of the heel-seats of boots and shoes for the attachment of heels such, for example, as wood heels.

Objects of the invention are to provide a tight joint between the periphery of the heel-seat of a heel such as a wood heel and the upper and to make a more artistic, accurate, permanent and satisfactory joint than heretofore.

In certain aspects the invention consists in providing the heel-seat of a shoe with a compacted or compressed inner area surrounded by a relatively soft, uncompressed, horseshoe-shaped area corresponding substantially to the shape and size of the outer rim or periphery of the seat of a heel such as a wood heel and, in the attachment of a heel, forcing said rim or periphery against the soft area to provide a tight joint between the heel and upper.

Preferably the entire heel-seat portion of the sole is compressed into a convex shape corresponding substantially to the cupped formation of the portion of the seat of the heel which covers it, the said compressed portion terminating in a groove or channel surrounding the periphery of the horseshoe-shaped heel-seat portion of the sole. The formation of this channel by compression tends to force outwardly the materials of the upper and counter beyond it and to form them into a rounded, non-compressed and therefore relatively soft bead located at the margin of the heel-seat and adapted to receive and permit to be embedded therein the rim of the applied heel, thus insuring a tight, unobtrusive joint between the heel and the heel-seat of the shoe.

In still another aspect the invention comprises a shoe construction characterized by a relatively hard, compressed heel-seat portion shaped to receive the concave heel-seat portion of a wood or other similar heel with a non-compressed, and therefore relatively soft, bead formed in the upper and counter materials and surrounding the compressed area, this bead receiving the marginal portion of the heel and yielding as may be necessary to permit the edge of the heel to embed itself in the bead and thus to make a tight joint.

These and other aspects of the invention will appear more fully from the following description when read in connection with the accompanying drawings and will be pointed out in the appended claims.

In the drawings:

Fig. 1 is a perspective view of a shoe the heel-seat of which has been prepared in accordance with the present invention for the attachment of a heel;

Fig. 2 is a perspective view showing the acting face of the heel-seat die;

Fig. 3 is a transverse section of the heel portion of a shoe, the heel-seat portion of which is being acted upon by the die shown in Fig. 2;

Fig. 4 is a view, similar to Fig. 2, of another form of die adapted for use in the practice of the present method;

Fig. 5 is a view, similar to Fig. 3, during the operation of the die shown in Fig. 4;

Fig. 6 is a sectional view of a shoe with the heel applied thereto under pressure; and

Fig. 7 is a fragmentary view, similar to Fig. 6, showing the heel permanently attached to the heel-seat.

This application is a continuation in part of our application Serial No. 507,614, filed October 14, 1921.

In order clearly to illustrate the invention, it has been shown in its relation to the manufacture of turn shoes having wood heels. It is to be understood, however, that, in various aspects, the invention is not so limited in its utility.

As shown in Fig. 1, the heel-seat portion of the shoe has been prepared by skiving the heel end of the sole to provide a breast covering flap *a* and a breast positioning flap *b*. The next operation upon the heel-seat is that of heel-seat fitting which consists in trimming away the peripheral portion of the heel-end *c* of the sole, this portion being, in a sewed seat shoe, whether a turn, McKay, or other shoe, the portion outside of the stitches. The heel-seat fitting operation is followed by a heel-seat forming operation in which the heel-seat is compressed by a die such as that shown in Fig. 2. The operating face 4 of the die is approximately cylindrically concaved at its forward portion, and at its rear portion is approximately spherically concaved. This surface extends uninterruptedly to the periphery of

the die where it meets a substantially vertical peripheral wall 6 of the die. Adjacent to the periphery of the surface 4, however, the angle of the surface to the outer wall 6 of the die increases slightly to form a narrow rim 8 about the periphery of the die, and the die is so shaped and proportioned relatively to the heel-seat that its inner portion will bear upon the rear end *c* of the sole while the extreme margin 8 forming the rim will bear upon the inner margin of the inturned upper *d* and counter *e* which, in a sewed heel-seat turn shoe, as illustrated, is along the line of stitching *f* attaching the upper and counter to the sole.

The result of the operation of the die upon the heel-seat, as shown in Figs. 1 and 3, is to compress the rear end *c* of the sole and give it a smooth, rounded convex shape which will correspond substantially to the interior portion of the cupped formation of the heel and to form in the inturned portion of the upper and counter adjacent to the sole a groove or channel *h* corresponding in shape to the rim of the heel but smaller. When the rim 8 of the die is forced into the upper and counter to form the channel *h*, the materials of the upper and counter underlying the rim 8 are compressed relatively to the portions outside of said rim and the inward bend of the upper and counter over the heel-seat is accentuated so that the counter and upper materials are formed into a rounded bead *i* extending around the periphery of the heel-seat and forming a non-compressed and relatively soft area to receive the rim of a heel such as a wood heel.

In order to present the most satisfactory appearance, a wood heel should be so attached that its outer surface forms substantially a continuation of the surface of the counter portion of the upper, the "rand crease" being practically obliterated. This result is easily obtained by our method, for as shown in Fig. 6, when a wood heel *k* of proper proportions is pressed upon a heel-seat formed as described, the rim *l* of the heel will be located upon the bead *i* and will be caused, by pressure applied before or during the heel attaching operation, to become embedded in the bead to form a tight joint between the heel and upper and to cause the surface of the counter portion of the upper to blend with the surface of the heel in smoothly curved lines without substantial break at the juncture of the heel and upper. A smooth stream line effect is thus obtained.

Glue is usually applied between the seat of the heel and the heel-seat of the shoe so that when these parts are pressed together, as shown in Fig. 6, firm adhesion will result when the glue is set. The heel is then securely attached to the shoe preferably by inside nailing as indicated at 26 in Fig. 7.

The die shown in Fig. 4 has the interior portion 20 of its operating face substantially like the surface 4 of the die shown in Fig. 2. This face terminates in a narrow horseshoe-shaped rim 22 outside of which is a transversely concaved forming surface 24 which also is horseshoe-shaped in outline. This die is so proportioned relatively to the heel-seat that the rim 22 will engage the upper and counter adjacent to the periphery of the sole. The heel end of the sole is confined within the concaved surface of the die when compressed and a groove or channel is formed by compression in the material of the heel-seat adjacent to the sole, while the peripheral portion 24 of the die outside of the rim 22 will act upon the upper and counter materials without substantial compression because they are unconfined against outward movement relatively to the die. The surface 24 of the die, however, acts to accentuate the peripheral bead formed on the upper and counter by the action of the rim 22 and causes the top of the bead to be located in a plane determined by the outer edge of the surface 24 of the die. The bead formed on the upper and counter is thus given a definite shape and height so that when a heel is applied to the bead in the manner shown in Fig. 6 and pressed therein and secured, as shown in Figs. 6 and 7, a uniform joint will be secured between the heel and upper.

Having thus described our invention, what we claim as new and desire to secure by Letters Patent of the United States is:

1. That improvement in methods of making shoes which consists in compressing the interior portion of the heel-seat of a shoe while leaving the margin thereof relatively soft and uncompressed, applying a heel with the peripheral rim of its seat in engagement with the soft periphery, pressing the heel in place, and securing it permanently to the shoe.

2. That improvement in methods of making shoes which consists in compressing the area of the upper and counter inside the area to be occupied by the peripheral margin of the heel-seat of a heel and thereby forming a relatively raised, uncompressed, portion about the periphery of the heel-seat of a shoe, applying a heel with the peripheral margin of its seat in contact with the said relatively raised portion, and pressing the heel in place to form a tight joint between the heel and upper and securing the heel to the shoe.

3. That improvement in methods of making shoes which consists in forming the interior portion of the heel-seat of a shoe into a smooth, convex area and the peripheral margin of the heel-seat into a rounded bead substantially of horseshoe shape, placing the peripheral rim of a heel upon said bead, ap-

plying pressure to sink said rim into the bead and securing the heel in place.

4. That improvement in methods of making shoes which consists in forming in the upper and counter materials of the heel-seat a groove or channel of horseshoe shape surrounded by a convex bead, locating the heel with the peripheral rim of its seat upon said bead, applying pressure to the 10 heel to flatten the bead, and securing the heel to the shoe.

5. That improvement in methods of making shoes which consists in compressing a portion of the heel-seat of a shoe and leaving a soft margin about said compressed portion, embedding the thin margin of the heel-seat portion of a heel upon the soft margin of the heel-seat, and fastening the heel in place.

20 6. That improvement in methods of making shoes which consists in compressing a horseshoe-shaped area upon the heel-seat, forming a horseshoe-shaped soft bead upstanding relatively to said area, and embedding the thin marginal edge of a wood heel in the bead with the peripheral surface of the counter and heel substantially in alignment.

7. That improvement in methods of making shoes which consists in depressing a horseshoe-shaped area of the surface of the heel-seat while the marginal portion of the heel-seat comprising the upper and counter is unconfined and remains relatively soft, 30 locating the rim of the seat portion of a wood heel upon said soft peripheral area, pressing the heel in place, and securing the heel to the shoe.

8. That improvement in methods of making shoes which consists in forming the peripheral portion of the heel-seat into an upstanding, rounded bead substantially of horseshoe shape, placing the peripheral rim of the heel upon said bead, applying pressure to sink said rim onto said bead, and securing the heel in place.

9. That improvement in methods of making shoes which consists in forming from the upper and counter materials of the heel-seat a bead, locating a heel with the peripheral rim of its seat face upon said bead, forcing the heel down upon the bead to form a tight joint between the heel and the upper, and securing the heel to the shoe.

10. A shoe having its heel-seat portion 55 surrounded by a bead and a heel secured to the shoe with its peripheral rim embedded in said bead.

11. A shoe having a heel-seat convexly shaped to correspond substantially to the 60 cup of the heel, said seat being surrounded by a bead and a heel secured to the shoe with its peripheral rim in engagement with said bead.

12. A shoe having the inturned portion 65 of its upper and counter at the heel-seat formed as a horseshoe-shaped bead extending along the periphery of the heel-seat and a heel secured thereto with its peripheral rim embedded in said bead.

13. A shoe having the inturned portion 70 of its upper and counter at the heel-seat formed as a bead extending about the periphery of the heel-seat and a heel secured thereto with its peripheral rim embedded in said bead and having its sides substantially flush with the sides of the counter portion of the shoe.

14. A shoe having the overlaid margins 75 of its upper and counter at its heel-seat shaped to form a channel surrounded by a compressible bead and a heel secured to the shoe with its peripheral rim embedded in the bead.

In testimony whereof I, the said JOHN 80 L. PREO, have signed my name to this specification.

JOHN L. PREO.

In testimony whereof I, the said ISABELLE HENNE, have signed my name to this specification.

ISABELLE HENNE.
